Fig. 2.

Des. 186,358

PAGE 3

FIG.3.

FIG. 4.

Fig. 1 is a side elevation of a baby's play-yard embodying my new design;

Fig. 2 is an end view of this play-yard looking at right angle to the view of Fig. 1;

Fig. 3 is a top plan view thereof; and

Fig. 4 is a side elevation of this play-yard, partially folded.

I claim:

The ornamental design for a baby's play-yard, substantially as shown.
